UNITED STATES PATENT OFFICE.

ALEXANDER BLOCK, OF NEW YORK, N. Y.

TYPEWRITING MACHINE.

1,403,836.

Specification of Letters Patent. Patented Jan. 17, 1922.

Application filed January 10, 1920. Serial No. 350,519.

To all whom it may concern:

Be it known that I, ALEXANDER BLOCK, a citizen of the United States, and resident of New York, in the county of New York 5 and State of New York, have invented certain new and useful Improvements in Type-writing Machines, of which the following is a specification.

This invention relates to typewriters, and 10 more particularly to inking mechanisms therefor, the main object of said invention being to provide a machine of the kind described herein with a multi-color inking mechanism of the type commonly employed 15 in printing machines, wherein regular printers' ink may be used, and means controllable by an operator for instantaneously shifting said inking mechanism so that the roller carrying the required colored ink may be 20 brought into inking position.

The present invention is an improvement on the machine disclosed in my application filed November 10, 1919. Serial No. 336,810. It differs from the machine disclosed in said 25 co-pending application in that it provides a segmental roller or two rollers having different colored inks, a sectional distributing cylinder, and a sectional ink fountain adapted to convey different colored inks to said roller. 30 The present invention is shown applied to a machine of the type disclosed in my co-pending application filed November 5, 1919, Serial No. 335,857.

The device embodied in the present invention constitutes improved means for inking the types in typewriting or like machines, and is intended to supersede the inking devices—such as ribbons or pads—now in common use.

40 Other objects consist in the novel features of construction described herein, and still others will appear in the specification, wherein like parts are represented by like characters throughout.

45 It is understood that I do not wish to limit myself to minor details of construction, nor to the use of this inking mechanism in connection with my machine described in my application of November 5th 1919, 50 which is used for the purpose of illustration only and not by way of limitation.

Figure 1 shows a top plan view of the machine, showing a view—from above—of the inking mechanism and its actuating 55 means, the carriage having been omitted,

parts broken away and other parts omitted. Figure 2 shows a left side elevation of the machine, parts broken away and parts omitted. Figure 3 is a right side sectional view of the machine, showing the inking mechanism and its shifting device. Figure 4 is a top view of the ink fountain and the fountain roller. Figure 5 shows the fountain roller and the ratchet wheel for rotating said roller intermittently. Figure 6 is a detail of the distributing cylinder. Figure 7 shows the combination ink carrying-distributor-form roller. Figure 8 shows the same—part in section. Figure 9 is the shaft upon which said roller is mounted. Figure 10 shows the device provided for conveying said roller from the ink source to the inking position. Figure 11 is an yielding member thereon. Figure 12 is a top plan view of the device for returning the inking mechanism to retracted rest position subsequently to the inking operation, parts broken away and part omitted. Figure 13 is the device in which said retracting mechanism is mounted, parts broken away, other parts being omitted. Figure 14 is a side elevation of the inking device, with parts in section and other parts omitted. Figure 15 is a detail of the sliding joint allowing of the shifting of said inking mechanism.

The machine frame 1 is of usual construction, embracing preferably a universal keyboard and parts for mounting the various mechanisms of the machine. Upon a supporting track 58 running transversely across the machine frame, near its rear end, is mounted said inking mechanism, which is arranged to slide thereon a distance for obtaining the required color of inking. The movement of said inking device on said track 58 may be facilitated by the use of anti-friction rollers or wheels 58^a and brackets 58^b for guiding said movements. The device for shifting said inking mechanism embraces a rocker shaft 40, preferably mounted in bearings 41—42, and provided at its inner end with an arm 39, to which is pivoted one end of a link 38, the other end of which is pivotally attached to a lug on said inking mechanism frame. On the outer extremity of said rocker shaft is mounted another arm 43 at about its middle, which arm is, or may be, provided at either end with a key 44, adapted to actuate said arm 43 for thereby to rock said rocker shaft 40.

and shifting said inking mechanism so that the roller carrying the required colored ink may be brought into inking position.

F designates a frame of said inking device arranged to be shifted upon said track 58, and upon or within which are mounted the various members of said device. An ink fountain 2 is mounted therein, and is divided into separate compartments 3^a—3^b by 10 a wall 3 adapted to hold different colored ink; said ink fountain comprising a knife 2^c for cutting up the ink as it is conveyed from the fountain by a fountain roller 4, mounted upon a shaft 4^b journaled in bearings in said fountain and adapted to rotate said fountain roller, and a ratchet wheel 4^a on said rotatable shaft 4^b which coacts with other means for intermittently rotating said fountain roller to intermittently 15 convey ink from the fountain to ink carrying members. Said fountain roller practically embraces two fountain roll members mounted on a common shaft, one for each fountain compartment, and is arranged to 20 receive and convey the different colored ink from said compartments. A distributing cylinder comprises preferably two or more distributing cylinder members 8—8 adapted for distributing different colored ink, a 25 grooved collar 11 separating said cylinders 8—8, and a third cylindrical member 10 provided with a grooved collar arranged obliquely around its circumference. Said distributing cylinder is or may be provided 30 with a longitudinal cylindrical opening and hubs 8^a—8^b for rotatably mounting said distributing cylinder upon flanges F¹—F² upon frame F. Upon one of said hubs 8^b is keyed a driving wheel for driving said 35 distributing cylinder on said flanges. In recesses in said flanges F¹—F² a shaft 17^t is rotatably mounted; upon which shaft are mounted arms 17 adapted to convey an ink carrying member 15 from its normal rest 40 position in contact with fountain roller 4 to its inking position for inking the type as it is being delivered to the printing point. Said arms 17 are provided at the lower end with a slot 17^t into which is taken the outer 45 ends of shaft 19 upon which said ink carrying member 15 is mounted. A toothed member 17^c on one of said arms is adapted to engage with ratchet wheel 4^a on shaft 4^b of fountain roller 4 and to actuate same for 50 intermittently rotating said fountain roller. Upon said arms 17 are pivoted yielding members 18 at 17^a which are held in normal position by a spring 18^x, one end of which spring is or may be attached to the 55 toothed member of said arm 17 and the other end to said yielding member 18, in the lower end of which is a recess or bearing wherein is journaled said inker shaft 19. The object of this arrangement of the yielding member 18 upon arms 17 is to allow 60

ink carrying member 15 to yield to the pressure of the type as it forces its way from inking position to a printing point, thus protecting both type and ink carrying member from damage. During the inking operation yielding members 18 are swung by the pressure of said type in the direction of the printing point against the action of spring 18^x, thus moving shaft 19 of ink carrier 15 in same direction along slot 17^t. 70 To one of the outer ends of shaft 17^v is keyed a ratchet wheel 6^c adapted to rotate said shaft and actuate arms 17 for delivering said ink carrying member 15 toward the inking position and to return it from said position to normal rest position in contact with said fountain roller 4. 80

Said ink carrying member comprises preferably two rollers 15 separated from each other by a grooved collar 15^a and mounted upon a shaft 19, said rollers being adapted for rotatable and slidable movement thereon; and are arranged to carry different colored inks. A slidable member 16 is provided with a stud 16^a arranged to be taken into said oblique grooved collar 10 on distributing cylinder 8 said stud coacting with said cylinder to impart to said ink carrying member a longitudinal to and fro sliding movement on shaft 19 while said rollers 15 are being 90 rotated upon said shaft 19 by frictional contact with said distributing cylinder 8. Shaft 19 embraces a substantially square part 19^c and a cylindrical part—sliding member 16 being mounted upon said substantially 100 square part and adapted for slidable movement thereon, while said ink carrying members 15 are mounted upon said cylindrical part of said shaft, and are adapted for rotatable and slidable movement thereon. One 105 of said ink carrying rollers 15 is or may be provided with a grooved collar 15^b into which is taken a flange on the inner end of said slidable member 16, and wherein said member 15 is adapted to rotate and whereby it is 110 moved slidably upon said shaft during the travel of said ink carrying member along the circumference of said distributing cylinder toward or away from said inking position. It is evident then that said ink carrying 115 member 15 not only functions as an ink carrying roller, but also as a distributor roller, for as its ink carrying rollers 15 are moved along the circumference of said distributing cylinders 8, by means of frictional contact with said cylinders, they are rotated and through slidable member 16 coacting by means of stud 16^a with obliquely grooved collar 10 on distributing cylinder 8, said rollers are furthermore given a longitudinal 120 to and fro movement along said distributing cylinders, and thus tend to evenly distribute the ink. Each of said rollers 15 having a different colored ink distributes said colored ink on distributing cylinder with which it 130

contacts, said grooved collar 11 separating said distributing cylinders and thus preventing the admixture of the different colors of ink during the to and fro movement of said 5 ink carrying-distributer rollers. Said rollers further function as form rollers when they are delivered by their actuating mechanism into the form inking position.

The driving means for said inking mechanism above described comprise a chain of 10 gearing operably connected with a keyboard; and consists of a main driving pinion 30 mounted upon a driven shaft 28 and driven by a ratchet 49. Upon the other end 15 of shaft 28 is mounted another pinion 31 which meshes with and is adapted to drive pinion 32 mounted upon driven shaft 33 which carries a member 34 provided preferably with a rectangular chamber or slot 20 adapted for taking in a key 37 on shaft 36 which is adapted to slide in said slot 35 during the shifting of said inking mechanism and to be rotated when said pinion 30 is driven by mechanism controlled from a 25 keyboard. On the inner end of shaft 36 is mounted another pinion 32^a which is meshable with and is adapted to drive pinion 12 keyed to one of the hubs of said distributing cylinder 8. A pinion 26 is meshable with 30 and adapted to be rotated by driving pinion 30 and is mounted upon a shaft 20, which is provided with a member embracing preferably a rectangular recess into which is taken a preferably rectangular key 22 on shaft 21 35 which is mounted in bearings in frame F. Upon said shaft 21 is preferably mounted an arm 5 to which is pivoted one end of a link 6^a, the other end of which link is pivoted to a ratchet meshable with ratchet wheel 6^c 40 and adapted to drive same and thereby actuate arms 17 and thus carry the ink carrying-distributer-form roller along the circumference of said distributing cylinder 8 toward and away from said inking position. 45 These two systems of driving means are arranged to be driven at differing speeds. As in the machine disclosed in my previous application filed November 10th, 1920, Serial No. 336,810, the gearing vary in size and are 50 so arranged relatively to each other, that when the said gearing is operated by mechanism controlled from a keyboard, the distributing cylinder is forced to move revolvably one or more times, while the inker is 55 being reciprocated into the inking position along the surface of said cylinder, a distance equal approximately to half the circumference of said distributing cylinder. The inker being in frictional contact with said 60 cylinder, it is forced to rotate a proportionate number of times by said cylinder during said transverse, and the slidable member of the inker coacts with said cylinder to impart a longitudinal to and fro movement to said 65 inker in addition to said rotary movement

during said traverse. Such construction causes a proper distribution of the ink. During the travel of said ink carrying-distributer-form roller a distance along the circumference of said distributing cylinder 70 from its rest grooved collar 11 on the distributing cylinder and 15^a on ink carrying member allow of the longitudinal to and fro movement of said ink carrying member without admixing of the different 75 colored ink.

Ratchet 49 arranged to drive main driving pinion 30 is adapted to move in guides, not shown, and is pivotally attached to a link 50, the other end of which is pivoted to a 80 bell crank 51 pivoted to machine frame 1 at 51^a; a link 52 being pivoted to the other arm of said bell crank 51 by one end and by the other to an operating lever 63 pivoted at 64 and adapted to be actuated by a spring 85 65. Normally said operating lever 63 is held in position of rest by a detent 85 against the action of said spring 65; said detent is pivotally mounted at 85^a, and is provided with a supporting arm 85, an actuating arm 90 86 and a stop 86^a abutting on a lug 89 on the machine frame 1. A spring 87 attached to lug 88 tends to maintain said detent 85 in normal position. A universal bar 90 is adapted to actuate said detent by the operation of key levers 80 pivoted at 81 and controlled from a keyboard 60—60; said universal bar 90 being adapted to depress arm 86 of said detent 85 against the action of spring 87 to release operating lever 63 and 100 allow spring 65 to move said lever in a direction to force the driving means herein described to operate said inking mechanism. Subsequently to the inking and printing operations the inking mechanism actuating 105 means and thereby the inking mechanism are returned to retracted rest position, preferably during the intermittent movements of the carriage, by a retracting device embracing a driven shaft 76 rotatably mounted 110 in machine frame 1; a pinion 77 mounted thereon and adapted to drive said driven shaft 76; another pinion 78 preferably beveled being mounted on said shaft and arranged to be driven thereby; another pinion 115 72—preferably beveled—being meshable with and normally disengaged from said pinion 78; a driven shaft 71 upon which pinion 72 is mounted and which is adapted to be driven by said pinion, an arm 70 having a guiding member 70^c mounted on said driven shaft 71 and adapted to be rotated thereby; a bell crank 68 pivoted at 68^b and having a free arm 68^a and a collar 71^a for housing driven shaft 71 which is adapted to 120 be rotated therein; a spring 78 attached to a support 79 tending to maintain said bell crank 68 and said retracting means 70—71—72 in normal position with pinion 72 disengaged from pinion 78; a cam 69 mounted 125 130

upon a rocker shaft 69^a being adapted to actuate said bell crank 68 to deliver pinion 72 into engagement with pinion 73 by the operation of the mechanism of the machine 5 controlled from a *c* keyboard and for maintaining said pinions in engagement during the operation of said mechanisms to allow of the operation of retracting arm 70 and thereby the returning of operating lever 63 10 to retracted rest position against the action of spring 65 and to force said operating lever into engagement with its detent 85 to be maintained thereby in normal position with said spring 65 under tension. Said retracting mechanism is adapted to be actuated by the means for moving the carriage during the intermittent movements of said carriage, said means comprising a rotatably mounted spring wheel 75 provided with a driving 15 gear 74 rotatable by said spring wheel, said gear 74 engaging with pinion 77 mounted on driving shaft 76 for driving said shaft.

It is evident that said inking mechanism is operated automatically, being actuated by 20 spring power under the control of an operator and is returned to retracted rest position by retracting means during the intermittent movements of the carriage, independent of the operator; the only effort required is to release the actuating means of 25 said inking device.

I have provided a machine of the kind embodied in my invention with a special type bar adaptable for use in connection with an 30 inking mechanism of the type disclosed herein. This type bar, however, is shown herein only by way of illustration and not by way of limitation, as it is evident that the type may be conveyed to the printing point past 35 the inking position in a variety of other ways. Type bar 48 is pivoted upon a segmental support at 48^a, comprising a type head with the type in such position as to be inked by the form roller of said inking 40 mechanism during its progress toward the printing point; an arm on said type bar provided with a slot 48^b adapted for taking in a stud 83^a on an arm 83 pivoted on machine frame 1 at 84; a link 82 being pivoted by 45 one end to said arm 83 and by its other end to a key lever 80 operated from a key 60. Said type bar 48 when delivered into the printing position subsequently to being inked by said form roller 15 does not directly 50 perform the printing operation, but delivers the type a distance from the paper. An impression bar 67 is actuated by mechanism 55 controlled from a keyboard to move toward said type and to press said paper against said type and thereby produce the impression on said paper. This type of printing mechanism is disclosed in detail in my application filed on November 5th, 1919, Serial 60 No. 335,857, and is touched upon briefly in 65 the present application. Means for regulat-

ing the degree of the impressing force is further provided in connection with this machine, and is more fully covered in said application of November 5th, said means partly comprising a rocker shaft 47 rotatably mounted in bearings on the machine frame 1 and having a threaded end 47^a for actuating said changeable means for regulating the impressing force of said impression bar, and fully illustrated and described and 70 claimed in said application of November 5th 1919; a crank 46 on said rocker shaft 47 being preferably situated at the front of the machine and of immediate access to an operator for easily regulating the impressing force by turning said crank in the required direction.

It is often desired to render the inking mechanism inoperative and I have provided means therefor, comprising a rocker shaft 85 54 mounted rotatably in bearings in the machine frame 1, and having an arm 61 mounted thereon and which arm is provided with a hook 62 which is arranged to be projected into the path of said operating lever 63 to prevent its being operated by spring 65 when released by detent 85 during the operation of the mechanisms of the machine as controlled from a keyboard. Upon the other end of said rocker shaft 54 preferably at the front of the keyboard is mounted another arm 55 at about its middle which may be provided with keys 56 adapted to depress said arm in either direction and to rock said shaft 54 and thereby swing arm 100 61 toward or away from operating lever 63 at the will of the operator. It is thus possible for an operator to instantaneously render said inking mechanism inoperative or operative as required. Furthermore, by 105 means of keys 44 it is rendered easy for an operator to instantaneously shift said inking mechanism to obtain the desired color for printing, and also by actuating crank 46 at the front of the machine to control 110 the degree of impressing force. It may be noted that my machine embodying the present invention is provided with a number of improvements that are of great advantage in a good typewriting machine and that 115 will be conducive to speed and the production of uniform beautiful printing.

In Figure 1 is shown a type bar in inking position, as it is being inked by said form roller 15, and in Figure 2 is shown said type 120 bar in printing position subsequently to its being inked.

In the preferred type of machine embodying my invention, the relative dimensions of pinions 30 and 58 are or may be 125 such that when pinion 30 is forced to make a revolution by the operation of the mechanisms of the machine as controlled from the keyboard, it causes pinion 58 to actuate arm 5 on shaft 27 for moving rollers 15—15 130

into and out of the inking position prior to the returning of the types to normal rest position; and during the retracting operation of lever 63, pinion 30 is caused to make 5 a revolution in the opposite direction and causes pinion 58 to actuate said arm 5 for again moving said inking rollers into and out of inking position subsequently to the printing operation and to the returning of 10 the types to normal rest position. However, the relative dimensions of the pinions 30 and 58 may be such that said pinion 30 in describing a revolution may cause pinion 58 to actuate arm 5 for moving the rollers into 15 inking position, and subsequently to the printing operation and during the retracting operation of lever 63 to cause the inking rollers to return to normal rest position.

The operation is as follows:
 20 When a key is depressed, key lever 80 bears down on universal bar 90 which in turn actuates detent 85 to release operating lever 63 which is actuated by spring 65 and moved in a direction to move downward 25 link 52 for actuating bell crank 54 to in turn through link 50 operate ratchet 49 and drive main driving pinion 30 and thereby rotate a number of times said distributing cylinder 8. Said main pinion 30 simultaneously rotates pinion 20 which through 30 its shafts 20-21 actuates toggle 5-6^a to force ratchet 6 to operate ratchet wheel 6^c which in turn forces the ink carrying-distributer-form roller to travel from its rest 35 position contacting with fountain roller 4 to the form inking position by means of rotating shaft 17^v which forces arm 17 to move forward toward said form inking position and to carry said form roller thereto. Simultaneously with the release of said inking 40 mechanism actuating means, key lever 80 causes type bar 48 to be swung toward the printing point to encounter in its path said inked form roller brought to the 45 form inking position and is inked thereby prior to its arrival at the printing position. The initial step is to bring pinion 72 into engagement with pinion 73 against the action of spring 78 by actuating bell crank 50 68 by cam 69 mounted on rocker shaft 69^a which is operated by mechanism controlled from a keyboard. When the key 60 is released the mechanisms are retracted to normal position, the inking mechanism being 55 returned to retracted rest position during the intermittent movements of the carriage, when the rotation of spring wheel 75 causes gear 74 to rotate pinion 77 which through driven shaft 76 causes the rotation of pinion 60 73 which in turn actuates retracting arm 70 through pinion 72 and driven shaft 71 driven thereby, said retracting arm 70 bearing down upon operating lever 63 to force it into engagement with detent 85 against 65 the action of spring 65. During the return-

ing of said operating lever to retracted rest position, said distributing cylinder is rotated in the opposite direction, arms 17 are forced to swing back toward normal position and to carry back said form roller 15 70 into contacting position with said fountain roller, said toothed member 17^c of arms 17 engaging with ratchet wheel 4^a which is forced to rotate by said toothed member during the return of said arms to normal 75 position, thus causing fountain rollers 4 to rotate and to convey fresh ink from the fountain to said ink carrying-distributer-form roller when it reaches a position contacting with said form rollers. 80

Having thus described the invention, what I claim as new and desire to secure by Letters Patent is:

1. In a typewriting or like machine, types movable to a printing position, an inking roller having different colored inks and arranged to move into and out of the path of movement of said types, means for moving said inking roller into the inking position, means separating the different colored inks 90 on said roller, and means for shifting the roller so that the portion carrying the required colored ink may be brought into inking position.

2. In a typewriting or like machine, types movable to a printing position, a sectional inking roller having different colored inks, means for moving said sectional roller into the inking position to ink the types as they approach the printing position, and means 100 for shifting the roller so that the section carrying the required colored ink may be brought into inking position.

3. In a typewriting or like machine, a sectional inking roller having different colored 105 inks and arranged to move into and out of the paths of movement of the types, means for impelling said inking roller into the inking position, means for shifting the roller so that the section carrying the required colored ink may be brought into inking position, and means cooperating with said roller 110 for distributing the inks evenly during the reciprocating movement of said inking roller into and out of inking position. 115

4. In a typewriting or like machine, inking rollers having different colored inks, said roller being adapted to move into and out of the path of movement of the types, means for reciprocating said inking rollers 120 into the inking position, a sectional ink fountain having different colored inks and adapted to convey different colored inks to said inking rollers, and a device cooperating with said roller for rendering said inks uniformly 125 smooth and even during the said reciprocating movement.

5. In a typewriting machine or the like, two inking rollers having different colored inks and arranged to move into and out of 130

- the paths of movement of the types, two ink fountains having different colored inks and adapted to intermittently convey a fresh supply of inks to said rollers, and two distributing devices cooperating with said rollers, for smoothing out uniformly and evenly the inks on said rollers during the movement of said rollers toward and away from said inking position, means being provided 5 for reciprocating said rollers into the inking position to ink the types as they approach the printing position.
6. In a typewriting machine or the like, types movable to a printing position, two inking rollers having different colored inks, said rollers being adapted to ink the types as they approach the printing position, spring means 10 for reciprocating said inking rollers into the inking position to ink said types, means cooperating with said rollers for maintaining the roller in normal rest position, manually operable means for releasing said inking rollers to allow of the inking operation, and means for shifting the rollers to allow of the 15 delivering into the inking position the roller having the desired colored ink.
7. In a typewriting machine or the like, inking rollers mounted on the same axis and having different colored inks, and a distributing device contacting with said rollers, each roller contacting with a corresponding member of said distributing device, means for reciprocating said inking rollers into the inking position, and to move revolubly during 20 its reciprocating movement into and out of the path of movement of the types, and a sectional ink fountain having different colored inks for intermittently conveying said inks to said inking rollers.
8. In a typewriting machine or the like, a plurality of inking rollers having different colored inks, a sectional distributing device, said rollers and said device being in frictional contact with each other, each roller 25 contacting with a corresponding section of the distributing device, mechanical means for reciprocating said inking roller into and out of inking position and causing said roller to move revolubly during said reciprocating movement on said distributing device, and a sectional ink fountain carrying a different colored ink in each section, additional means being provided for conveying said colored inks from said fountain to said inking roller.
9. In a typewriting machine or the like, types, two inking rollers having different colored inks, a two section ink fountain having different colored inks, each section of said fountain being arranged to convey ink 30 to the corresponding inking roller, means for reciprocating said rollers into and out of the paths of movement of the types, and two distributing cylinders cooperating with said rollers for rendering the inks uniformly even during the reciprocating movement of 35
- said rollers, means being provided for shifting the inking mechanism so that the roller carrying the required colored ink may be brought into inking position.
10. In a typewriting machine or the like, 40 a plurality of inking rollers having different colored inks, a plurality of ink fountains carrying different colored inks, each fountain being arranged to supply ink to its corresponding ink roller, means for conveying ink from each fountain to its corresponding roller, mechanical means for reciprocating said rollers into and out of the paths of the types, and shifting mechanism for shifting the rollers so that the roller carrying the required colored ink may be brought into inking position.
11. In a typewriting machine or the like, an inking mechanism including a sectional inking roller and a sectional rotatable distributing cylinder, said roller being arranged to carry different colored inks and being in frictional contact with said cylinder, a sectional ink fountain having different colored inks for intermittently supplying said inking roller with different colored inks, and power means to operate said inking mechanism for automatically reciprocating said sectional roller into and out of inking position.
12. In a typewriting or like machine, a plurality of inking rollers having different colored inks, types movable to a printing position, said inking rollers being movable in cycles into and out of inking position, and means to control the movement of said types and said inking roller in a predetermined relation, and means for shifting the rollers so that the roller carrying the required colored ink may be brought into inking position.
13. In a typewriting or like machine, a plurality of inking rollers having different colored inks, a plurality of distributing cylinders, said rollers being in frictional contact with said cylinders, each roller contacting with a corresponding cylinder, types, mechanical means causing said rollers to traverse the circumference of said cylinder a distance to the inking position to ink the types as they approach the printing position, and means causing said distributing cylinders to move revolubly and by frictional contact to cause said roller to be rotated during the travel of said inking rollers toward and away from the inking position, means being provided for shifting the rollers so that the roller carrying the required colored ink may be brought into inking position.
14. In a typewriting or like machine, a plurality of inking rollers having different colored inks, a plurality of distributing cylinders contacting with said rollers, each cylinder with a corresponding roller, and a carrier for reciprocating said inking rollers

into and out of inking position, said rollers being automatically adjustable on said carrier to yieldingly resist the pressure of the types during the inking operation, means being provided for shifting said rollers so that the roller having the required colored ink may be delivered into inking position.

15. In a typewriting machine or the like, inking rollers having different colored inks, a sectional distributing element contacting therewith, types movable to a printing position, a frame carrying said rollers and adapted to move said rollers a distance along the surface of said distributing element to the inking position for inking said types, a holder pivotally supporting said frame, and means to operate said holder for moving said inking rollers into and out of the path of movement of said types, shifting mechanism being provided for shifting the roller carrying the required colored ink so that said roller may be brought into inking position.

16. In a typewriting machine or the like, types movable to a printing position, a plurality of inking rollers having different colored inks, holders for said rollers, carriers pivotally supporting said rollers, means to yieldingly centralize said holders on said carriers, means to operate said carriers for reciprocating said inking rollers into and out of the path of movement of said types, and means for shifting the rollers so that the roller carrying the required colored ink may be moved into inking position.

35. 17. In a typewriting or like machine, types, a sectional inking roller having different colored inks, holders for said roller, carriers pivotally supporting said holders, springs yieldingly centralizing the holders on the carriers, stops adapted to limit the pivotal movement of the holders in either direction, and means causing the carriers to reciprocate said sectional roller into and out of the path of movement of said types, shifting means being provided to shift the roller so that the section carrying the required colored ink may be brought into inking position.

50. 18. In a typewriting or like machine, types movable to a printing position, a sectional distributing element, a sectional inking roller contacting therewith and having different colored inks, holders for said sectional roller, carriers pivotally supporting said holders, a shaft supporting said carriers, and means associated with said shaft for actuating the carriers to cause said carriers to reciprocate the sectional roller into and out of the path of movement of said types, means being provided for shifting the roller so that the section carrying the required colored ink may be brought into inking position.

55. 19. In a typewriting or like machine, types, a sectional distributing cylinder, a sectional ink fountain having different

colored inks, a shaft journaled therein, a sectional fountain roller on said shaft adapted for intermittent rotation, a sectional inking roller having different colored inks, said roller being in constant frictional contact 70 with said distributing cylinder, and normally contacting with said fountain roller, a section of said inking roller being normally in apposition with a corresponding section of said fountain roller, holders for 75 said inking roller, carriers pivotally supporting said holders, a toothed element associated with said carriers, means to operate the carriers for reciprocating said inking roller into and out of the path of movement 80 of said types, means for delivering at the inking position the desired section of said inking roller, and means on said shaft cooperating with said toothed element for intermittently rotating said fountain roller to 85 deliver a freshly inked surface of said fountain roller to the inking roller as said inking roller is approaching its normal rest position to contact with the fountain roller.

20. In a typewriting machine or the like, 90 inking rollers mounted on the same axis and having different colored inks, types, distributing cylinders, a frame mounted for pivotal movement, pivotal arms on said frame arranged to carry said inking rollers, a ratchet 95 wheel for actuating said frame to reciprocate said rollers into and out of the path of movement of said types, automatically actuated mechanism for operating said ratchet wheel, and a device for returning said automatically actuated mechanism to normal rest position and for maintaining said rollers in said position, and means for shifting the rollers so that the roller carrying the required colored ink may be brought into inking position.

21. In a typewriting machine or the like, two inking rollers having different colored inks, types movable to a printing position, means for moving said rollers into the inking position to ink the types as they approach the printing position, said inking rollers being movable into and out of the path of movement of said types and being universally adjustable to automatically accommodate themselves to the pressure of the types as they move from the inking position to the printing position, and means for shifting the rollers so that the roller carrying the required colored ink may be brought into inking position.

22. In a typewriting or like machine, a plurality of inking rollers having different colored inks, means to automatically reciprocate said rollers into and out of inking 115 position, types arranged to be inked by said rollers as they approach the printing position, said rollers being universally and automatically adjustable on said reciprocating means to accommodate themselves to the 120

pressure of the types as they are moved from inking to printing position, and means for shifting the rollers so that the roller carrying the required colored ink may be brought into inking position.

23. In a typewriting or like machine, a frame movably mounted upon a support in the machine frame, an inking device supported in said frame and including a distributing element and a sectional inking roller having different colored inks, means for reciprocating said roller into and out of the path of movement of the types, and means controllable by an operator for shifting the frame so that the section of said roller carrying the required colored ink may be brought into inking position.

24. In a typewriting or like machine, a frame movably mounted on the machine frame, an inking mechanism supported therein, said mechanism including a distributing cylinder mounted for revoluble movement in said frame, and inking rollers having different colored inks, and contacting with said cylinder, actuating means in operative connection with said inking mechanism for simultaneously revolving the cylinder and for reciprocating the inking roller into and out of inking position, shifting mechanism for said frame controllable by the operator, and loose connections in said actuating means to allow of the shifting of said frame so that the roller having the required colored ink may be brought into inking position.

25. In a typewriting machine or the like, types, a frame adapted for slidable movement on the machine frame, an inking mechanism supported therein, said inking mechanism including a plurality of inking rollers having different colored inks and a sectional fountain adapted to convey ink to said rollers, a plurality of distributing cylinders mounted for revoluble movement in said frame, carriers pivotally supported on said frame, holders for said rollers pivotally supported on said carriers, automatic means for actuating said carriers to reciprocate said rollers into and out of the path of movement of said types, and mechanical means controllable by an operator for moving said frame a distance so that the roller carrying the required colored ink may be brought into inking position.

26. In a typewriting or like machine, types movable to a printing position, an inking mechanism including a plurality of inking rollers and a plurality of distributing cylinders, said rollers being movable into and out of the path of movement of the types, holders for said rollers, carriers pivotally supporting said holders, means for actuating said carriers to reciprocate said rollers into the inking position for inking the types as they approach the printing posi-

tion, and means removably attaching said inking rollers to said carriers.

27. In a typewriting machine or the like, types, a plurality of distributing cylinders, a plurality of inking rollers contacting with said cylinders and arranged to carry different colored inks, a member associated with said rollers contacting with a corresponding member associated with said cylinders, mechanical means causing said cylinders to move revolvably and to simultaneously reciprocate said inking rollers into and out of the inking position along the surface of said distributing cylinders, frictional means causing said inking rollers to be rotated during their traverse toward and away from said inking position, and further means for imparting a longitudinal movement to said inking rollers during their traverse in addition to the rotary movement, means being provided for shifting the inking mechanism to allow of the delivering at the inking position the inking roller having the required colored ink.

28. In a typewriting or like machine, an inking mechanism adapted to ink types as they approach the printing position, said mechanism including a distributing cylinder divided into sections and a sectional inking roller having different colored inks and contacting frictionally with said sectional cylinder, means for intermittently conveying a fresh supply of ink to said inking roller, means causing said roller to move along the circumference of the cylinder a distance to be reciprocated into the inking position for inking the types as they approach the printing position, means causing said distributing cylinder to revolve simultaneously with the traverse of said roller along its surface, said frictional means being adapted to impart a rotary movement to said roller during its reciprocatory movement, and further means for imparting a longitudinal to and fro movement to said roller during said traverse, shifting means being provided for moving said inking mechanism a distance to allow of the delivering to the inking position the desired section of said roller.

29. In a typewriting or like machine, a sectional distributing cylinder, a sectional inking roller having different colored inks and contacting with said distributing cylinder, a slidable member associated with said inking roller, means causing said roller to move a distance along the surface of said cylinder into the inking position, said means simultaneously causing said distributing cylinder to revolve and to impart a rotary movement to said roller during its travel, a stud on said slidale member, a grooved collar on said distributing cylinder into which said stud is adapted to be taken, said grooved collar cooperating with said stud to impart a reciprocating movement longi-

tudinally to said type inking roller during its traverse, and means controllable by an operator for shifting the inking mechanism to allow of the delivering to the inking position of the section of said roller having the desired colored ink.

30. In a typewriting or like machine, an inking mechanism including a plurality of distributing cylinders and a plurality of inking rollers having different colored inks, said roller being adapted to move into and out of the path of movement of types, reciprocating means causing said inking rollers to move along the surface of said cylinder a distance to the inking position, said means causing said cylinder to simultaneously move revolubly and to impart a rotary movement to said rollers during their reciprocating movement, an element associated with said cylinders and having a grooved collar, a slidible member associated with said inking rollers and having a stud, said grooved collar being adapted to receive said stud and to cooperate therewith for imparting an endwise longitudinal to and fro movement to said rollers, and mechanism controllable by an operator for shifting said mechanism to allow of the feeding to the inking position of the desired roller.

31. In a typewriting or like machine, a plurality of inking rollers having different colored inks, a sectional fountain arranged to carry different colored inks and to convey said inks to said rollers, a shaft journaled in said fountain, a sectional fountain roller on said shaft adapted for intermittent rotation, holders for said inking rollers, carriers pivotally supporting said holders, means for actuating said carriers to move said rollers into and out of the inking position, and means associated with said shaft coacting with means associated with said carriers for intermittently rotating said sectional fountain roller to deliver a freshly inked surface thereof to said inking roller as said inking roller is approaching its normal rest position to contact with said fountain roller, shifting means being provided to allow of reciprocating into the inking position the roller having the desired colored ink.

32. In a typewriting or like machine, an inking mechanism, driving means therefore, an operating lever for actuating said driving means, said mechanism including a plurality of inking rollers having different colored inks and a distributing cylinder in frictional contact therewith, means for actuating said lever to cause said driving means to reciprocate said inking rollers into and out of inking position, types adapted to be inked by said rollers, and means for the returning of the operating lever to normal rest position subsequently to the printing operation, means being provided for shift-

ing the rollers so that the roller having the required colored ink may be brought into inking position.

33. In a typewriting or like machine, an inking device including inkers having different colored inks, driving means therefore, an operating lever, means operably connecting said driving means with said lever, mechanical means for impelling said lever in a direction to force said driving means to 70 actuate said inking mechanism, types movable to a printing position, means cooperating with said lever for maintaining the lever in normal rest position, manually operable means for releasing said lever to allow said mechanical means to operate the lever, said driving means and said inking device for inking the types as they approach the printing position, and means for returning said lever, said driving means and 80 said inking device to normal rest position, and means for shifting said inking device so that the inker carrying the required colored ink may be brought into inking position. 90

34. In a typewriting machine or the like, types, an inking device including inkers having different colored inks and adapted to ink said types, gearing adapted to drive said mechanism, a ratchet in operative connection with said gearing, an operating lever, mechanical means for impelling the lever in a direction to cause said ratchet to operate the gearing and force said inking device to ink the types as they approach 95 the printing position, and retracting means for the returning of the operating lever to normal rest position, means being provided for shifting the inkers so that the inker carrying the required colored ink may be brought into inking position. 100

35. In a typewriting machine, key-controlled types movable to a common printing position, an inking device having a sectional inking roller adapted to carry different colored inks, gearing for operating said inking device, a ratchet for driving said gearing, mechanical means operably connected with a keyboard for actuating said ratchet to cause said gearing to operate the inking device for reciprocating said sectional inking device into and out of the paths of movement of said types, and means for shifting said roller so that the section carrying the required colored ink may be 110 brought into inking position. 115

36. In a typewriting machine, a series of key-controlled types movable to a common printing position, an inking device including inkers having different colored inks, 125 gearing for operating said device, and power means for driving said gearing to cause said inking device to ink the types as they successively approach the printing position, and means for shifting the inking 130

device so that the inker having the required colored ink may be brought into inking position.

37. In a typewriting machine, types movable to an inking position and then to a common printing point, an inking mechanism including inkers having different colored inks, gearing for operating said mechanism, a ratchet for driving the gearing, an operating lever, spring means for impelling said lever in a direction to cause said ratchet to drive the gearing for causing said inking mechanism to successively ink the types as they approach the printing position, and means for shifting the inking device so that the inker having the required colored ink may be brought into inking position.

38. In a typewriting machine, an inking device having a plurality of inking rollers, said rollers being adapted to carry different colored inks, a system of gearing, a ratchet for operating said gearing, an operating lever, a spring for impelling said lever in a direction to force the ratchet to drive said gearing for reciprocating the inking rollers into and out of the inking position, a series of key controlled types movable to a common printing position, a detent cooperating with said operating lever for maintaining said lever in normal rest position, a key-actuated universal bar causing said detent to release said lever to allow of the inking of the types as they approach the printing position, and a retracting device cooperating with said operating lever for the returning of the lever to normal rest position subsequently to the printing operation, and means for shifting the rollers so that the roller carrying the required colored ink may be brought into inking position.

39. In a typewriting or like machine, a distributing cylinder, inking rollers having different colored inks and contacting frictionally with said cylinder, an ink fountain having different colored inks, holders for said inking rollers, carriers pivotally supporting said holders, a main driving pinion in operative connection with said cylinder and adapted to rotate said cylinder, a pinion meshing with said main driving pinion and in operative connection with said carriers for actuating said carriers, and power means for operating said main driving pinion to cause said distributing cylinder to move revolubly and to simultaneously cause said carriers to reciprocate said inking rollers into the inking position for inking the types as they approach the printing position, means being provided for shifting the rollers so that the roller having the required colored ink may be brought into inking position.

40. In a typewriting machine or the like,

an inking mechanism including a distributing cylinder and a sectional inking roller contacting therewith, said roller having different colored inks, holders for said inking roller, carriers pivotally supporting said holders, two systems of driving means in operative connection with each other, one of said systems in operative connection with said cylinder being adapted to rotate said cylinder, the other of said systems being adapted to actuate said carriers for reciprocating the inking roller into and out of inking position, and mechanical means for operating said systems of driving means simultaneously to reciprocate said inking roller into said inking position and to rotate said cylinder during the traverse of said roller, and by means of frictional contact of said roller with said cylinder cause the rotation of said roller during its reciprocating movement, and means for shifting the roller so that the section carrying the required colored ink may be delivered into inking position.

41. In a typewriting or like machine, an inking mechanism including inkers having different colored inks, power means for operating said inking mechanism and a power operated retracting device for returning said mechanism to normal rest position, and means for shifting the inking mechanism so that the inker having the required colored ink may be brought into inking position.

42. In a typewriting or like machine, a sectional inking roller having different colored inks, an operating lever for reciprocating said roller into and out of the inking position, mechanical means for impelling said lever in a direction for actuating said inking roller, a detent cooperating with said lever for maintaining the lever in normal rest position, means for releasing said lever to allow of the inking operation, and a power operated retracting device cooperating with said lever for the returning of said lever to normal rest position and means for shifting the roller so that the section having the required colored ink may be delivered into inking position.

43. In a typewriting machine, a power operated inking mechanism adapted to reciprocate a plurality of inking rollers into and out of inking position, a series of types movable to a common printing position and adapted to be inked by said rollers as they severally approach the printing point, means for maintaining said inking rollers in normal rest position, key actuated means for releasing the reciprocating mechanism to allow of the inking operation, and a retracting device for returning said reciprocating means and said inking rollers to normal rest position, said rollers being arranged to move into and out of inking position.

tion upon being actuated by said reciprocating mechanism, and to again move into and out of the inking position during the retracting operation, means being provided 5 for shifting the rollers so that the roller having the required colored ink may be brought into inking position.

44. In a typewriting machine, types movable to a common printing position, an inking device having a sectional inking roller, said roller being adapted to carry different colored inks, actuators for operating said inking device to cause the inking roller to ink the types as they severally approach the 10 printing position, means for maintaining said actuators and said device in normal rest position, key actuated means for releasing said actuators to allow said sectional roller to be automatically reciprocated into 15 20 and out of the paths of movement of said types, and a power operated retracting device cooperating with said actuators for the returning of said actuators to the retracted position subsequently to the printing operation 25 and means for shifting the roller so that the section having the required colored ink may be delivered into inking position.

45. In a typewriting machine, a series of types movable to a common printing position, 30 an inking mechanism having inking rollers adapted to carry different colored inks, actuators for automatically operating said inking mechanism to cause said inking rollers to be reciprocated into the inking position for inking the types as they are severally approaching the printing position, a 35 retracting device, and automatic means for actuating said retracting device to cause said device to cooperate with said actuators 40 for the returning of said actuators and said inking rollers to normal rest position subsequently to the printing operations, means being provided for shifting the rollers so that the roller having the required colored 45 ink may be brought into inking position.

46. In a typewriting machine, a series of types movable to an inking position and then to a common printing position, an inking device having inking rollers adapted 50 to carry different colored inks, actuators for operating said mechanism and causing said rollers to be reciprocated into and out of the paths of movement of said types, a detent for maintaining said actuators in normal 55 rest position, key controlled means for releasing said actuators to allow of the inking operation, a driven shaft, a retracting device mounted thereon and adapted to be driven thereby, and automatic means for 60 driving said driven shaft to cause said retracting device to cooperate with said actuators for the returning of the actuators to normal rest position and into engagement with its detent, means being provided for 65 shifting the rollers so that the roller having

the required colored ink may be brought into inking position.

47. In a typewriting machine, types movable to a common printing point, an inking mechanism having inkers carrying different 70 colored inks, actuators for operating said mechanism and for reciprocating said inkers into and out of the paths of said types, a driven shaft, a toothed wheel arranged to drive said shaft, a retracting mechanism 75 upon said shaft and adapted to be driven thereby, and means independent of the operator for causing said toothed wheel to operate said retracting mechanism and to return the actuators to normal rest position 80 subsequently to the printing operations, means being provided for shifting the inkers so that the inker having the required colored ink may be brought into inking position. 85

48. In a typewriting machine, types movable to a common printing position, an inking mechanism, having inkers carrying different colored inks, actuators for operating said mechanism for inking the types as 90 they severally approach the printing position, power for operating said actuators, a driven shaft, a retracting device thereon and adapted to be driven thereby, a toothed wheel associated with said shaft and adapted to drive the shaft and the retracting device, a carrier revolubly supporting said driven shaft, automatic means for operating said toothed wheel to cause said retracting device to cooperate with the actuators for 100 the returning of said actuators to normal rest position, said toothed wheel being normally disengaged from its actuating means, and means for actuating said carrier to deliver said toothed wheel into engagement 105 with its actuating means and allow of the retracting operation, means being provided for shifting the inkers so that the inker having the required colored ink may be brought into inking position. 110

49. In a typewriting machine, types movable to a common printing position, an inking mechanism including inkers having different colored inks and adapted to ink said types as they severally approach 115 the printing position, actuators for said mechanism, a carrier, a retracting combination revolubly supported therein, said combination comprising a driven shaft, a toothed wheel for driving said shaft, and a 120 retracting device upon said shaft and adapted to be driven thereby, means for maintaining said carrier and said retracting combination in normal rest position, automatically operated mechanism for operating 125 said retracting device, said toothed wheel being normally disengaged from said automatically operated mechanism, and means for moving said toothed wheel into engagement with said automatic mechanism to 130

allow of the operation of said retracting device and of the returning of said actuators to normal rest position, means being provided for shifting the inkers so that the 5 inker having the required colored ink may be brought into inking position.

50. In a typewriting machine, types movable to a common printing point, an inking mechanism, including inkers having 10 different colored inks, actuators for operating said mechanism to cause said mechanism to ink said types as they approach the printing position, a carrier, a retracting combination revolubly mounted therein, a spring 15 for maintaining said carrier and said retracting combination in normal rest position, automatic means for actuating said retracting combination, said combination being normally disengaged from said automatic 20 means, and key controlled means for actuating said carrier and delivering said retracting combination into operative engagement with its automatic actuating means for operating said retracting device 25 to cause said device to return to normal position said inking mechanism actuators, means being provided for shifting the inkers so that the inker having the required colored ink may be brought into inking 30 position.

51. In a typewriting machine, types movable to a common printing point, an inking mechanism including inkers having different colored inks, actuators causing said 35 mechanism to ink the types as they severally approach the printing position, a driven shaft, a retracting device mounted thereon and adapted to be driven thereby, a toothed wheel upon said shaft and adapted to drive 40 the shaft and the retracting device, a carrier for revolubly supporting said shaft and the devices associated therewith, driving means for said toothed wheel, a spring for maintaining said carrier in normal rest position 45 with the toothed wheel disengaged from its driving means, key-controlled means for actuating said carrier against the action of its spring to deliver the toothed wheel into engagement with its driving means, and 50 means for actuating said driving means to force said retracting device to return said actuators to normal rest position, means being provided for shifting the inkers so that the inker having the required colored 55 ink may be brought into inking position.

52. In a typewriting machine, types movable to a common printing position, an inking mechanism including inkers having different colored inks, actuators causing 60 said mechanism to ink said types as they severally approach the inking position, a carrier, a rocker shaft rotatably mounted therein, a retracting device on said shaft adapted to be operated thereby, a toothed

wheel upon said shaft arranged to drive 65 said shaft, means for driving said toothed wheel, means for maintaining the carrier in normal rest position with said wheel disengaged from its driving means, a spring for maintaining said retracting device in 70 normal rest position with reference to said carrier, key actuated means for moving said carrier into operative position for delivering said toothed wheel into engagement with its driving means, a carriage adapted 75 for intermittent movement, power for moving said carriage and for actuating said driving means during said intermittent movements of the carriage to force said retracting device to cooperate with said inking mechanism actuators for the returning of said actuators to normal rest position, means being provided for shifting the inkers so that the inker having the required colored ink may be brought into inking 80 position.

53. In a typewriting machine, types movable to a common printing point, an inking mechanism including inking rollers having different colored inks, actuators for 90 said inking mechanism, said actuators causing said mechanism to ink the types as they approach the printing position, a retracting device cooperating with said actuators for the returning of said actuators to normal 95 rest position, and means for guiding said retracting device into engagement with said inking mechanism actuators, means being provided for shifting the inkers so that the inker having the required colored ink may 100 be brought into inking position.

54. In a typewriting machine or the like, an inking mechanism including inking rollers having different colored inks, types, said mechanism being adapted to reciprocate said rollers into and out of the path of movement of said types, means for maintaining said mechanism in normal rest position, manually operable mechanism for releasing said inking mechanism to allow of 110 the inking operation, means for retracting said inking mechanism, and means controllable by an operator and adapted to be moved into the path of movement of said actuators for throwing said mechanism out 115 of operation, means being provided for shifting the inkers so that the inker having the required colored ink may be brought into inking position.

55. In a typewriting machine or the like, 120 an inking mechanism having a sectional inking roller adapted for carrying different colored inks, types, an operating lever, mechanical means for impelling said lever in a direction for reciprocating said roller 125 into and out of the paths of said types as they approach the printing position, means cooperating with said lever for maintaining

the lever in normal rest position, manually operable mechanism for releasing said lever to allow of the inking operation, a device for automatically retracting said lever and 5 said inking roller, and a mechanical device controllable by an operator and arranged to be moved into the path of movement of said operating lever for throwing said lever and said mechanism out of operation at the will 10 of the operator, and means for shifting the roller so that the section having the required

colored ink may be delivered into inking position.

Signed at New York (1843 Madison Av.,) in the county of New York and State of 15 New York, this 8th day of January, A. D. 1920.
